(57) **CLAIM**

The ornamental design for a blooming cross, as shown and described.

DESCRIPTION

FIG. 1 is a front, top perspective view of the blooming cross showing my new design;

FIG. 2 is a diagonal, front / right side, elevational view thereof;

FIG. 3 is a front and rear, elevational view thereof;

FIG. 4 is a right side and left side, elevational view thereof;

FIG. 5 is a top view thereof; and,

FIG. 6 is a bottom view thereof.

The broken line showing of the base of the blooming cross forms no part of the claimed design.
